WILLIAM H. FURNESS, OF NATIONAL PARK, NEW JERSEY

ART OF RAYON MANUFACTURE

Application filed April 7, 1930. Serial No. 442,473.

This invention relates to improvements in manufacturing rayon and it has for one of its primary objects provision of a method and apparatus whereby rayon of fine denier of 5 fine quality may be rapidly, effectively and economically manufactured.

Heretofore it has been not only difficult to spin fine denier threads but also such yarn has been very expensive to produce because 10 thereof and because of the excessive losses in the various operations in the manufacture of the finished yarn, following the spinning.

It is an object of my invention to overcome 15 these disadvantages.

A further object of the invention is to cheapen production by increasing the output 20 of the spinning machines.

Still another object of the invention is to provide a new form of thread which may be 25 used in the form produced, or readily divided into a number of threads of smaller denier.

Still another object of the invention is to multiply the output of a spinning machine 30 with very little increase in cost.

The foregoing, together with such other 35 objects and advantages as may hereinafter appear, or are incident to my invention, are realized by a method, the preferred form of which I will now proceed to describe, the invention being set forth in connection with the cuproammonium process of silk manufacture for which my invention is best adapted. A means for carrying out the process is illustrated in the drawing, in which-

Figure 1 is a diagrammatic front elevation 40 of spinning, drawing, and cap twister mechanism suitable for one step of my process;

Figure 1a is a fragmentary plan view of the spinneret arrangement of Figure 1;

Figure 1b is a fragmentary side elevation 45 of the cap twister arrangement;

Figure 1c is a diagrammatic sectional elevation of decopping mechanism suitable for another step of my process, and

Figure 1d is a diagrammatic elevation of mechanism suitable for carrying out the final 50 step of my process.

In carrying out my invention I prepare a solution of copper hydrate, ammonia and cel- 55 lulose, preferably using minimum dissolving

proportions and then diluting with water to secure the desired concentration, say, for example, three and one-half to four percent cellulose. This is in accordance with my co-pending application Serial No. 181,614, filed 55 April 6, 1927 and since issued as Patent No. 1,770,750, on July 15, 1930.

This solution, after filtering, is pumped through a multiple spinneret such, for example, as a double, triple or quadruple spinneret. The filaments are spun into a caustic bath, the bath solution being one which causes the precipitation of the solution into non-adherent filaments which are recommended as giving the best results. 65

Taking a double spinning for example, the feed pipe 2 leading from the pump is forked at its end 3 and has a spinneret 4 on each fork (see Figures 1 and 1a). If it is desired to make, for example, a thread of 100 denier by this process, a thread of 50 denier would be spun by each of the two spinnerets, each spinneret having the desired number of spinning openings and the number of spinning openings being equal in each in order to 70 get uniform flow of the solution.

The filaments are precipitated in the bath 75 before they merge into the threads.

The two threads are then drawn out of the precipitating bath and passed over two drawing wheels 6 and 7 which may be of different size, running at the same speed, or of the same size, running at different speeds, as described in my copending application Serial 80 No. 239,401, filed December 12, 1927, the purpose of the drawing wheels being to impart 85 such a stretch to the thread as will remove the extensibility due to precipitation of the solution in gel form. I believe that the stretching so imparted collapses the cells, or, rather, elongates them by extruding some of the liquid, but without thinning down of the thread by a physical stretching such as would impair, by stretching, the fibers constituting the cell walls. 90

The two threads are passed first around one wheel and then the other wheel, and there are two guides 8 beyond the drawing wheels, one for each thread, suitable guides 9 and 10 also being provided at the point where the 100

threads emerge from the precipitating bath, and to guide the threads over the wheels.

The two threads, after leaving the drawing wheels, pass through the guides aforesaid and are wound upon a bobbin or spool by cap twister mechanism 11 such as shown and described in my copending application Serial No. 239,403, filed December 12, 1927, and since issued as Patent No. 1,829,986, on November 3, 1931.

This cap twister mechanism lays the two threads up as one thread upon the spool 12, imparting to each thread a twist and imparting a twist to the single heavy thread made up of the two light threads much after the manner of a two strand rope.

There is now upon the spool 12 a single thread ultimately producing, when conditioned, a thread of 100 denier.

20 When the spool is filled, it is doffed from the spinning machine and the thread is unwound and passed through an acid bath 13 (see Figure 1c) after the manner described in my copending application Serial No. 239,404, filed December 12, 1927, to remove copper and since issued as Patent No. 1,853,123, on April 12, 1932.

As the thread is being unwound from the spool for passage through the acid bath, a spray 14 of mildly caustic water is applied thereto to remove caustic soda. Because the spray plays upon the spool as it is being unwound, the entire length of the thread is uniformly subject thereto. The balance of the caustic is removed in the acid bath 13.

30 The thread is drawn through the acid bath and unwound from the spool by winding it upon a large spool or cylinder 15, such, for example, as shown and described in my copending application Serial No. 381,199, filed July 26, 1929, and since issued as Patent No. 1,811,386, on June 23, 1931. This large spool or cylinder preferably revolves partly in the acid bath.

40 45 The thread is preferably laid upon the cylinder after the manner described in my copending application Serial No. 239,405, filed December 12, 1927 and since issued as Patent No. 1,770,397, on July 15, 1930, with a traverse motion, producing a cake which is uniformly pervious to water and which has its edges tapered or chamfered so as to secure uniform exposure of the thread throughout its length.

50 55 After the cylinder is filled, it is washed in water preferably by revolving the cylinder and causing a jet of water to travel lengthwise of the cylinder. The water is on preferably during only one stroke of the pipe, which may be a rubber hose attached to a suitable supply line and connected to a traverse motion which gives it a reciprocatory movement. This is economical in water consumption and yet gives effective washing out

of the acid throughout the length of the thread.

After the washing operation the cylinder is put into a drying oven and the thread dried.

70 The thread may now be used in this form in which it is, as it were, a cable of two strands, the strands being twisted, one about the other, and the filaments of each strand being twisted.

75 If, however, the thread is to be divided into two threads of fifty denier each, the operator breaks off an end of the thread, which causes the two strands to readily separate.

80 For separation it is desirable to proceed as follows. The conditioned thread is unwound from the cylinder 15 and wound on to a bobbin 16, which bobbin is placed in a horizontal position in a support 17 revolving about a vertical axis 18 (see Figure 1d).

85 The thread is led through a guide 19 and to and between a pair of feeding rolls 20 which are driven at constant speed, as is the revolving spool. After the thread has been led through the guide and through the feeding rolls, the end is broken off, which makes it possible for the operator to readily separate the two strands of the single thread. Each strand is led through a suitable guide 21 and then to an ordinary cap twister 22 for laying up upon a spool.

90 95 In operation the thread is unwound from the spool 16 revolving in a horizontal plane, passes through the feed rollers 20, and then the two strands are laid upon their respective spools 23.

100 105 By mounting the spool which is being unwound in a horizontal plane in a support revolving about a vertical axis, the twist which was imparted by the first cap twisting operation following the drawing wheels previously described is removed. If this were not done, it would be impossible to divide the thread because the twist would run back along the thread, making it impossible in a short while to continue operations through breakage or otherwise. Each strand, however, is again twisted in the final cap twisting operation after the thread leaves the feeding rolls.

110 115 The feeding rolls and the revolving support are preferably driven at such speeds that the twist and no more and no less than the twist, is removed. This can be readily determined by experiment.

120 125 In order to facilitate separation after the thread is divided into two strands, one strand passes to one side and the other strand to the opposite side of a finger 24 intermediate the feed rolls and the final cap twisters. This finger, therefore, is located at the apex of the Y formed. The finger is movably mounted to reciprocate in a direction longitudinally of the thread, the finger extending transversely of the thread at the apex of the Y.

It will be seen from the foregoing that with a spinning machine and the other apparatus necessary to produce a single thread, I can produce double, triple, quadruple, the 5 yardage, etc. Furthermore, it will be quite evident to those skilled in the art that I carry a single relatively heavy thread throughout all of the operations in manufacture which can be readily and effectively done without 10 the breakages, such as would occur if it were attempted to carry a single thread of fine denier through the system. Thus I effect a great economy and, at the same time, secure perfect threads, the divided threads being as 15 perfect as the thread from which they are divided. Another advantage of forming such a thread in manufacture is that if a filament breaks, it can only run a certain distance along the thread before running of the 20 filament is stopped because of the cable construction of the thread.

Again it will be seen that by spinning two or more fine threads, I am enabled to increase the speed of spinning for the reason 25 that the surface tension in the precipitating bath on the individual fine threads is much less than it would be on a single heavy thread. Thus, for example, if it were desired, it would be possible to spin two fine 30 threads at approximately twice the rate of a single thread of the combined denier of the two light threads.

It will be seen from the foregoing that I am enabled to simply and effectively produce fine denier threads with the same apparatus which is used for producing single threads of heavier denier and with all the safety with which the heavy threads can be produced and with greater dispatch and 40 with but a fractional increase in cost.

It will, of course, be understood that I can produce, for example, two threads of 75 denier from a thread of 150 denier, or three threads of 50 denier from a thread of 150 denier, and so on, and this with threads the 45 filaments of which are of the order of the filaments of natural silk.

While I have described my invention more particularly when making a combined 50 thread of two threads of lighter denier, I

prefer to make thread from more than two strands for the reason that if it is desired to use the heavy thread produced as is, it will be of more uniform cross section. It will be apparent that such a thread of cable construction can be effectively used in fabricating certain kinds of cloth and the like, and that it can be effectively and rapidly fabricated without liability of breakage or without taking the precautions which are frequently necessary in order to successfully fabricate the yarn of the cloth.

Furthermore, by spinning of a single thread of non-adherent filaments, I can divide it as described. The multiple spinning, however, is preferred as it is more easy to divide the thread and there is less possibility of injury to the threads.

I do not make any claim herein to the mechanism which I employ in carrying out the aforesaid process, the same being set forth and claimed in my copending application Serial No. 331,781, filed January 11, 1929.

I claim:

1. The herein described process which comprises forming rayon threads of light denier, uniting them into a heavy thread with a twist therein, treating said heavy thread, and dividing it into its component threads while removing the twist imparted.

2. The herein described process which comprises forming rayon threads of light denier, uniting them into a heavy thread with a twist therein, treating said heavy thread, and dividing it into its component threads while removing the twist imparted and twisting said component threads.

3. The herein described process which comprises forming rayon threads of light denier, laying up said threads in the form of one heavy thread while imparting twist thereto, unwinding said thread and dividing it into its component threads while removing the twist imparted, and laying up the component threads while imparting twist thereto.

In testimony whereof I have hereunto signed my name.

WILLIAM H. FURNESS.
